UNITED STATES PATENT OFFICE.

WILLIAM JAMES HOWELL, OF FLUSHING, NEW YORK.

APPARATUS FOR PRODUCING INDENTED TYPE-IMPRESSIONS.

SPECIFICATION forming part of Letters Patent No. 423,688, dated March 18, 1890.

Application filed June 6, 1889. Serial No. 313,284. (No model.)

To all whom it may concern:

Be it known that I, WILLIAM JAMES HOWELL, of Flushing, Queens county, New York, have invented a new and useful Improvement 5 in Apparatus for Producing Indented Type- Impressions upon Paper, &c., of which the following is a specification.

My invention relates to a machine for producing indented type-impressions upon paper 10 or other material, which impressions may subsequently be used as stereotype-molds.

My invention consists in the construction of the apparatus, as hereinafter more particularly set forth, in which the material which 15 is to form the matrix, and in which the type are to produce their indentations, is disposed in front of an annular type-cylinder, in which cylinder are radial chambers in which the type are placed. The hammer is disposed in- 20 side the cylinder, and is actuated to strike and press on the protruding rear end of any one of the type which may be presented to it. The types are movable longitudinally and are arranged in the same horizontal plane as the 25 hammer, so that the rotation of the cylinder on its axis brings any one of the type in place in front of the hammer. Consequently when the hammer delivers its stroke it causes the type in front of it to move longitudinally, so 30 that the type is driven into the paper, wax, or other material which is to form the matrix. This material is then moved a certain distance to the right to space the letters, and the cylinder is again adjusted so as to bring another 35 type in front of the hammer, and this type is caused to indent itself in the same way, and thus a series of indentations is made upon the paper corresponding exactly to the letters which would be printed by the type if the 40 faces of the type were inked. The matrix being thus formed is removed from the machine, and serves as a mold for stereotyping or elec- trotyping in metal in the ordinary way.

The important features of my invention 45 are, first, the annular type-cylinder in which the movable type are disposed, within which cylinder is arranged the hammer which moves the individual type longitudinally and outwardly to cause them to produce their im- 50 pressions; second, the hammer and its associated mechanism, which causes the hammer to strike not a sudden blow on the type, but

to force or press the type into the material of the matrix for a measured distance; third, the construction of the hammer mechanism 55 so that it shall act positively on the hammer and operate with greatest force when the hammer approaches the end of its inward stroke, and hence has forced the type most deeply into the matrix; fourth, the mechanism whereby 60 a rotary type-wheel is turned in different positions by the oscillation or vibration of a pivoted bar or plate operated upon by wedges or cams placed at different distances from the center of oscillation, said cams being associ- 65 ated with the finger-keys; fifth, the construction whereby power from an outside source is caused to actuate the various mechanisms embodied, so as to reduce the manual labor of the operator practically to such as is nec- 70 essary only for the adjustment of the parts and the regulation of the time of applying the power; sixth, the novel construction of the letter-spacing mechanism; seventh, the various novel combinations and sub-combinations 75 of mechanism, all substantially as hereinafter set forth.

In the accompanying drawings, Figure 1 is a vertical section of the machine on the line X X of Fig. 2. Fig. 2 is a plan view. Fig. 80 3 is an end elevation of the machine, looking toward the rear side of the movable carriage. Fig. 4 is a sectional view taken on the same line as Fig. 1, and showing corresponding parts on a larger scale. In Figs. 1 85 and 4 the finger-keys are shown in a different position, as will be more fully set forth hereafter in this specification. Fig. 5 is a detailed view, showing the mechanism arranged on the rear side of the carriage for operating 90 the spacing device. Fig. 6 is a side view of the same mechanism. Fig. 7 is a sectional view, on the same line as in Fig. 1, of the mechanism for operating the type-striking hammer, the said mechanism being shown on 95 an enlarged scale, and the link-levers being in a different position from that indicated in Fig. 1. Fig. 8 is a vertical section on the line a a of Fig. 7. Fig. 9 is an enlarged longitudinal section of one of the type-receiving 100 compartments on the line b b of Fig. 10. Fig. 10 is a partial sectional view of the type-cylinder on the line c c of Fig. 11. Fig. 11 is a side elevation of the type-cylinder 57. Fig.

12 is a partial section and plan on the line *d-d* of Fig. 1. Fig. 13 is a front elevation of the moving carriage and paper-receiving frame thereon. Fig. 14 is a section on the line *ee* of Fig. 13. Fig. 15 is a section on the line *ff* of Fig. 12. Fig. 16 is a detailed view, showing the mode of connection between the band 52 and the bar 15. Fig. 17 is a face view of the graduated wheel 116, showing 10 graduations thereon. Fig. 18 shows the curved fulcrum-bar 3 separately. Fig. 19 is a section through the support 50, just above the bolt 85.

Similar numbers of reference indicate like 15 parts.

I will first describe the mechanism whereby on the pressure of a finger-key a movable type is adjusted in proper place in front of the material upon which the character is to 20 be impressed, and which mechanism, by continuing its operation, causes the type to be struck by the hammer and moved outwardly, so as to produce said impression. 1 is the table or bed of the machine, on which are 25 two standards 2. Between the standards 2 extends a curved fulcrum-bar 3, (dotted lines, Fig. 2,) which passes through holes in the keys 4. It will therefore be understood that when any one of the ten keys 4 is struck by 30 the finger in the ordinary manner of the type-writer key it will vibrate on its pivot-bar 3. Said keys are separated by washers (indicated at 5.)

The casing of the machine is formed in 35 two parts, the lower part 6 being secured directly to the bed 1 and the upper part 7 resting upon the part 6 and also upon the two standards 8, Fig. 1. The part 7 is secured in place by the three screws 9, which enter 40 the lower casing 6, and also by the screws 10, which enter the ends of the standards 8. By removing these screws the upper casing 7 can be separated from the lower casing, so as to allow of access to the interior mechanism.

45 The casing 6 is open in front, as shown at 11, Figs. 1 and 4, so that the keys may extend through it. On the under side of each of the keys 4 is a cam projection 12, and also a pin 13. The side of the projection 12 nearest the 50 pin is beveled or inclined, so as to form a cam-surface. Pivoted at its middle to a standard 14, rising from the bed 1, is a semi-circular plate or bar 15, to which are attached cords 17, which cords are connected to the 55 ends of springs 18, inclosed in suitable casings, Fig. 2. It will be understood that when the curved plate 15 is vibrated horizontally on its central pivot it will be opposed by the action of one or other spring 18, and that the 60 tendency of the springs will be to bring the plate always back again to its original position. The extremities of the curved plate 15 rest upon curved rails 19, which are supported upon standards 20, as shown in Figs. 1 and 13. 65 As a key 4 is pressed downward, the straight bottom face of its projection 12 comes in contact with a semicircular plate 21, which ex-

tends underneath all the keys and which is supported upon rods 22, which rods rise from another curved plate 23. Plate 23 is supported on a series of arms 24, (dotted lines, Fig. 13,) which radiate from the lever-arm 25, which lever-arm is pivoted at 26 to a bracket 27, which extends downward from the frame 1. Consequently when the lower edge of the 75 projection 12 meets the plate 21 it forces that plate, and hence the plate 23, downward, and so causes the lever 25 to vibrate on its pivot 26.

At the end of the lever 25, Fig. 7, is a slotted link 28, into which enters the pin 29 on 80 the dog 30. The dog 30 is made in two parts, as shown in sectional view, Fig. 8, and from each part projects a pin or roller 31, each of which pins enters a cam-groove 32, formed upon the faces or brackets 33 34.

85 35 is a bent lever pivoted to the bracket 36, which depends from the bed 1. The downwardly-bent end of lever 35 is connected by a spiral spring 35* to a pin which extends between the lower extremities of the parts of 90 the dog 30. The lever 35 is pivoted between the upper faces of the dogs 30, and also on the same pivot between said dogs is a lever 37. In the extremity of the lever 37 is a slot 37*, through which passes a pivot-pin which connects said lever with the hammer-rod 38.

95 Each of the dogs 30 is provided with a shoulder or step 39, which is suitably placed so as to be engaged by the teeth of the wheel 40. The wheel 40 is supported on the shaft 41, 100 which extends between suitable bearings 41*, Fig. 3, depending from the bed 1. On said shaft is a pulley 42, by means of which motion is communicated to said shaft by a belt 43 from an electric motor or other suitable 105 source of power, the pulley, and hence the wheel 40, being rotated in the direction of the arrow. The wheel 40 is loose upon the shaft 41, but is provided with a segmental opening 44, Fig. 7, in which enters a projection 45 from 110 the shaft. The projection 45 meets the end of the opening, and so carries the wheel around with it.

115 Between the projection 45 and the end of the opening in the wheel is interposed a spiral 120 spring 46. The object of this spiral spring is to act as a cushion, so as to prevent too sudden movement of the wheel 40 and possible disarrangement of the mechanism. Beneath the projection 12 is also disposed a curved 125 bar 134, which is supported upon two bent rods, one of which is shown at 135, which extends down between the two fixed rollers 136. It is pivoted to the bar 23 at 137.

130 On projection 12 of the key 4 is a hook or shoulder portion 138. When a key is raised, as shown in Fig. 1, the bar 134 stands partly under the bar 21; but when the key is depressed the effect of the rollers 136 with the bent rod 135, which is carried through them 130 downwardly, is to move the bar 134 to the left of the drawing, so that the hook 138 on the key engages with said bar 134, as shown in Fig. 4.

The operation of the apparatus so far described will now be explained. When the key 4 is pressed down, the straight lower end of the projection 12 first strikes the bar 21, thereby forcing downward the plate 23 and raising the slotted link at the end of the arm 25. The effect of the raising of the slotted link 28 is to cause the rollers 31 and the dog 30 to traverse the cam-groove 32, so that the toe or shoulder 39 on the dog 30 is brought into position to be acted upon by the teeth of the wheel 40. The effect of throwing forward the dog, so as to bring its shoulder 39 into position for engagement, is also to carry upward the levers 35 and 37; but the lever 37, by reason of the slot 37* therein, then moves over its pivot-pin in the end of the hammer-lever 38, so that during this motion of the dog no movement is communicated to the hammer-lever. Consequently the only resistance to the downward pressure of the key is the inertia and friction of the few parts necessary to be moved to bring the dog into proper position to be acted upon by the wheel. As already explained, the descent of the plate 21, forcing down the bar 23, throws the locking-plate 134 to the left, so that it engages with the hook 38 on the projection 12, under the key 4; hence by the time the wheel 40 begins to act on the shoulder 39 to carry it up the key 4 is locked to the plate 134, and hence the rotation of the wheel, raising the lever-arm 25, pulls down the key 4 still farther. The further operation of the machine is then done by the outside source of power acting upon the wheel 40, and it will therefore be understood that the manual work of the operator consists simply in forcing down the key sufficiently far to throw the shoulder 39 on the dog 30 into position to be acted upon by the wheel 40, and simultaneously to cause a locking of the key to the levers, which are now to be moved by the wheel. The wheel in rotating carries up the dog 30 to the upper arch of the cam-groove 32, and in so doing brings the levers 35 and 37 into a horizontal position, as shown in Fig. 7; but before the lever 35 reaches this horizontal position the end of its slot 37* will meet the pin in the end of the hammer-lever 38 and carry the hammer-rod 38 to the right of Fig. 4 against the action of the spring 38*, attached to said rod. Inasmuch as said rod is pivoted at 47, its upper end, which carries the hammer 48, is brought into contact with one of the type. How this hammer operates in connection with the type will be described farther on. As soon as the dog reaches the upper arch of the cam-groove 32 it is carried over said arch by the action of the spring 35, and then the dog descends by gravity, its roller following the opposite side of the cam-groove 32, and thus resumes its normal position. The hammer is then retracted by the spring 38*. One action, therefore, of the wheel 40 is to cause the hammer 48 to strike the type; but in the meantime the wheel

is, as already explained, raising the lever 25, and hence moving down the plate 23, to which the key has been locked. Consequently as the key goes down the front inclined edge of the projection 12 meets the inner side or edge of the curved plate 15 and causes that plate to vibrate on its central pivot. If the key which is pressed down is located just on one side of the central pivot, it will be obvious that the plate 15 will be displaced or caused to oscillate over a greater arc than when it is acted upon by a similarly-arranged key placed at a greater distance from the pivot; hence no two of the keys 4 will swing the plate 15 over the same distance in the arc. It will be understood, however, that the keys located on opposite sides of the pivot 14 will cause the plate 15 to oscillate in the relatively opposite directions. By the greater or less movement of the plate 15 the type-cylinder is rotated so as to bring the type into position so as to be struck by the hammer. How this is done will be described farther on. Meanwhile attention is now called to the projection or pin 13, which projects downward from the key 4. This pin, when the key 4 is pressed down, enters a hole (one of a series) in the plate 15, which is suitably disposed to receive it, as shown in Fig. 4. It does not reach this hole until after the plate 15 has been moved by the projection 12. Of course when the pin 13 enters the hole in plate 15 plate 15 can no longer oscillate on its pivot, and therefore the object of the pin 13 is to prevent too much oscillation of the plate 15, because if the key were suddenly drawn down the plate 15 might in that case swing a little beyond its proper point. If as soon as the plate 15 is adjusted the pin 13 enters the opening and locks it, it will be obvious that no further motion of plate 15 can ensue.

I will now refer to the type mechanism. Extending up from the bed 1 is a tube 49, and surrounding this is a loose tube or sleeve 50. Upon said tube 50 is a chain or sprocket wheel 51. The sprocket-chain 52 passes over fixed pulleys 53, (dotted lines, Fig. 12, and dotted lines, Fig. 2,) and is connected to the ends of the swinging bar 15 by means of a screw-bolt 53*, as shown in Fig. 16. In order to prevent slackening of the chain when the bar 15 oscillates, I provide an arc-shaped plate 54, which is carried by said plate 15 by downwardly-depending arms 55, Fig. 15. This curved bar 54 rests upon a roller 56, which is supported on the bed 1. The ends of the chain, after passing around the pulleys 53, extend over the periphery of this curved bar to the end of bar 15. It will be understood, therefore, that when the bar 15 is oscillated on its central pivot it rotates the sleeve 50, and that the extent of rotation of the sleeve 50 will be in either direction proportional to the arc swung over by the bar 15.

57 is the type-cylinder shown in partial horizontal section in Fig. 10 and in elevation in Fig. 11. This consists of an annular piece

of metal or hard rubber provided with a series of compartments radially arranged. Each chamber or compartment is of suitable size to contain one of the type 58, Fig. 10. On each type is formed a shoulder 61 of suitable size nearly to fill up the cross-section of this compartment and move freely therein. The inner end of the type projects through an opening in the rear of the compartment and into the central space 59. The front end of the compartment is closed by a plate 60, of metal, which enters a recess in the cylinder. The outer ends of the types pass through said plates, as shown in Fig. 10. Surrounding each type, and interposed between its shoulder and plate 60, is a spiral spring 62. Extending downward from the type-cylinder 57 is a sleeve 63, which fits over the tube 50 and rests upon the ring or collar 64, as shown in Fig. 4. The inner ends of the type, projecting into the annular space 59, lie in the plane of motion of the hammer-head, and therefore it will be obvious that by rotating the cylinder 57 any type may be brought in front of the hammer, so as to be acted upon thereby.

To recapitulate briefly, therefore, the operation of the mechanism so far described, when a key 4 is pressed down it first throws the shoulder of the dog 30 into position to be acted upon by the wheel 40; or, in other words, arranges matters so that the power applied to the machine may go on and do the work. The wheel in rotating pulls the key down farther, and the key in going down farther swings the plate 15, and thus rotates the type-cylinder 57, so that a certain type corresponding to the key which is pressed is brought in front of the hammer. Then the wheel, still operating, actuates the hammer to strike the type, and thus causing the type to impress itself upon the paper or other material disposed to receive it, and, lastly, the dog is retracted from engagement with the wheel, the lever 25 descends, the key 4 is unlocked and returns to its normal position, and the dog resumes its original place ready to be thrown into engagement with the wheel again when a key is once more pressed.

I will now describe the spacing mechanism, whereby the material to be indented is caused to move in front of the type, so that the indentations may be disposed thereon in the proper order to produce the desired words, &c. Extending downward from the upper case 7 is a bracket 66, Fig. 4, to which is pivoted a swinging bail 67, which extends over the ends of the keys 4, so that by pressing any one of said keys the bail 67 may be swung on its pivot. Connected to said bail is a rod 68, which works the spacing mechanism. The rod 68 is secured to a lever 69, which is pivoted to a bracket 33 at 92. The end of the rod 69 is forked, and in the fork is received the lower extremity of a bar 94, Fig. 3. Upon one side of said bar are formed rack-teeth, Fig. 5, which engage with a pinion 95, which is supported on the rear side of the

carriage 96 in a bracket 97. (See Figs. 1, 3, and 5.) 98 is the pinion-shaft, which terminates in a gear 99, this gear being placed just inside the rear face of the supporting-carriage 96, Fig. 1. Surrounding said pinion-shaft is a spring, (not shown, but inclosed in the cylindrical casing 97*, Fig. 6,) which acts upon a fixed abutment on the bracket 97, and also on the pinion-shaft is a ratchet 100, (dotted lines, Fig. 5,) which acts upon a pawl 101, which pawl acts upon the pinion 95. The operation of this spring is to cause the pinion normally to turn in one direction. 102 is a bent bar also having on its edge rack-teeth adapted to engage with pinion 95, and provided on its horizontal portion with two rollers 103 on opposite sides of the bar 94. The bar 102 is pivoted at 104. Extending downward from the upper flange of the carriage 96 are two brackets 105 and 106, to which are pivoted levers 107 108, which carry at their ends rollers which bear against opposite sides of the bar 94. The spiral spring 110 extends from the pivoted lever 108 to the hook end of the bracket 106. A similar spiral spring 109 extends from the pivoted lever 107 to the upper flange of the carriage 96. Upon the brackets 105 and 106 are shoulders 105* and 106*, for limiting the movements of the arms 107 and 108 when said arms are retracted by the springs 109 and 110. As the rod 94 moves downward, the tendency of the lever 108, acted upon by spring 110, is to crowd the rod 94 against the pinion 95, and so cause engagement of the rack-teeth of rod 94 with the teeth of pinion 95, and simultaneously it moves rod 102, so as to throw that rod to the left and out of engagement with the pinion. At the same time the lever 107 drops down (see Fig. 5) and allows of this inward swing of rod 94 in direction of the arrow, Fig. 3. Then as the rod 94 continues its downward motion it rotates the pinion 95 and is assisted by the action of the spring on the pinion-shaft. On the upward motion of the rod 94 the levers 107 and 108 assume the positions shown in Fig. 3, and the rod 94 moves away from the pinion 95. At the same time the rod 94 draws the rod 102 into engagement with the pinion, and thus the pinion is locked in place until the rod 94 makes another downstroke, when the foregoing operation is repeated. The carriage 96 is provided with a dovetail slide 111, which enters ways 112 on the bed or table 1. Extending upward from said carriage is a fixed nut 113, Fig. 1; also extending upward from the table 1 are brackets 114, in which brackets is journaled a screw 115, which is turned by the hand-wheel 116. By turning the hand-wheel 116 the carriage 96 may be caused to slide in its ways, and so brought nearer to or farther from the type-cylinder 57. On top of the bracket 114 is fastened a fixed pointer 117, and I may lay off the rim of the hand-wheel 116 in any convenient divisions, so that the pointer 117 will show the extent to which the wheel has been

turned, and thus the extent of movement of the carriage may be nicely graduated and observed.

I will now describe the device which holds 5 the paper or other material upon which the type are to produce their impressions. The front view of this device is shown in Fig. 13. 118 119 120 are the vertical members and transverse member of a frame of light thin 10 metal, such as steel. In the lower portion of this frame is journaled a roller 121. About half-way up said frame is the rack-bar 122, and, finally, on the upper end of the members 118 119 is journaled another roller 123, which 15 is supported in brackets 124. Between the rear end of the brackets 124 extends a bar 125, Fig. 3, and depending from this bar is a small bracket 126, which carries a roller 127. The roller 127 runs on a rail 128 on the upper 20 surface of the carriage 96. On the lower front side of the carriage 96 is arranged a small horizontal roller 129, against which the other member 120 of the paper-frame bears. It will be understood, therefore, that the paper-frame is held between the roller 129 and 25 the carriage 96, and that it is supported upon the roller 127, which rests upon the rail 128. The roller 121 enters and freely moves in a circular chamber 130 in the carriage 96. The rack-bar 122 enters and freely moves in a similar but smaller chamber 131, extending across the face of the carriage 96. Therefore the frame 118 119 120 is free to slide longitudinally 30 crosswise the face of the carriage 96. The inclosing-wall of the chamber 131, which receives the rack-bar 122, is slotted on its under side, so that the pinion 99 may project therein and engage with the rack-bar 122. A handle or knob 132 is provided for convenience in 35 turning the roller 123.

The spacing-key 133, Fig. 2, is a simple lever not provided with the downward projection 12. It is pivoted upon the bar 3. Its rear end acts upon the bail 67 to raise the rod 45 68, and thus through the lever 69 to operate the bar 94 in the manner already described.

It is of course important that the type-cylinder should not be free to oscillate or turn loosely on its center at all times, but that it 50 should be held in position firmly, except just when it is rotated to set a type in front of the hammer. I therefore provide a locking mechanism, which normally prevents the sleeve 50 from rotating, but which is released when a 55 key is pushed down. Secured to the rod 68 is a spring toe or stop 83, which acts upon the pivoted bell-crank lever 84, and the lever 84 operates a sliding spring-bolt 85. In the sleeve 50 is a slot which receives said bolt, 60 so that when the bolt is in the slot the sleeve 50 is locked and prevented from turning. The arrangement of the spring toe or stop 83 upon the rod 68 is such that the lever 84 is 65 acted upon to withdraw the bolt, and thus leave the sleeve 50, and hence the cylinder 57, free to turn just before the key 4 commences to act on the swinging plate 15.

Any one skilled in the art will readily understand that the various motions heretofore described are to be so timed, and hence the mechanism is to be so adjusted and arranged, that the various operations will follow in their proper order, and this order recapitulated is as follows: First, a key is pressed down, throwing the dog into position to be engaged by the wheel and simultaneously locking the key to the wheel through the intermediate devices, so that the key receives motion from the wheel; second, as the key is drawn down it operates the lever 84 and releases the type-cylinder, so that the latter is now free to be turned; third, as the key continues to go down it vibrates the plate 15, and so sets the type-cylinder in position to bring the type corresponding to that key in the path of the hammer; fourth, the pin 13 on the key then enters a hole in the plate 15 and locks that plate from further motion, and by this time the toe 83 has passed the bell-crank lever 84 and the spring-bolt 85 has been again thrown by the action of its spring into the slot in the sleeve 50, thus once more locking the cylinder in place; fifth, by this time the lever 37 is acting upon the hammer to force it against the type, causing said type to make its indentation; 85 sixth, the key 4 now raises the bail 67 sufficiently to operate the spacing mechanism; seventh, the dog now passing the arch of the cam-groove 32 goes back to its normal position, the key 4 is released, and the parts resume their condition as at starting.

I have shown in the type-cylinder only ten type; but of course it will be understood that I may arrange more type in said cylinder, so as to increase the number of characters. A 105 machine of ten type, however—each one representing one of the numerical digits—has a special utility for the preparation of stereotyping-molds for arithmetical tables and like work.

It is to be distinctly understood that the drawings forming part hereof are not working drawings, nor are they drawn to any definite scale, nor are the parts represented in exact relative sizes and proportions; but any 115 mechanic skilled in the art will readily comprehend how the parts are to be modified or arranged to bring about the proper timing and co-ordination of the movements. The sleeve 63 of cylinder 57 simply surrounds the tubular support 50, so that the said cylinder and sleeve are easily detachable from the tube. It is desirable in practice to provide several cylinders 57, having different type, all interchangeable upon the support 50. In this way 125 the capacity of the machine for imprinting different characters is greatly augmented.

I claim—

1. The combination of the pivoted plate 15, two keys, as 4, located at different distances 130 from the pivot of said plate and each provided with a cam projection 12, acting upon and vibrating said plate when either key is depressed, the rotary type-carrying cylinder

57, and gearing between said plate 15 and said cylinder for transmitting the motion of said plate to said cylinder, substantially as described.

5 2. The combination of the pivoted plate 15, springs 18, attached at one end to fixed supports and at their other ends, respectively, to the extremities of said plate, the key 4, having cam projection 12, acting upon and vibrating said plate when said key is depressed, the rotary type-carrying cylinder 57, and gearing between said plate 15 and said cylinder for transmitting the motion of said plate to said cylinder, substantially as described.

15 3. In combination with the key 4, carrying the cam projection 12, the pivoted plate 15, acted upon and vibrated by said cam, springs 18, attached at one end to fixed supports and at their other ends, respectively, to the extremities of said plate, the curved bar 54, carried by said plate, the type-cylinder 57 and rotary support therefor, and the belt or chain 52, passing around said rotary support and connected at its ends to the extremities of 25 said curved bar 54, the said belt or chain transmitting the motion of said bar 15 to said cylinder 57, substantially as described.

4. A support, a type 58, longitudinally movable therein, the pivoted hammer 48 in rear 30 of said type and operating to press upon and longitudinally move said type, a motor, the spur-wheel 40, rotated by said motor, and the movable shouldered dog 30, supported in proximity to said wheel and connected to the 35 shank of said hammer, in combination with the finger-key 4 and transmitting mechanism between said key and said dog for moving said dog on the depression of said key into engagement with said wheel, the said wheel, 40 when said dog is engaged as aforesaid, causing said hammer to vibrate on its pivot and press upon said type, substantially as described.

5. The combination of a support, a type 58, 45 longitudinally movable therein, the pivoted hammer 48 in rear of said type and operating to press upon and longitudinally move said type, a motor, the spur-wheel 40, rotated by said motor, a fixed support having the 50 cam-groove 32, the movable dog 30, having a pin or roller traveling in said cam-groove and provided with a shoulder 39, disposed in proximity to said spur-wheel 40, link 37, connecting said dog 30 to the hammer-lever, key 4, 55 and pivoted lever 24 25, the said lever 24 25 being vibrated on its pivot when said key 4 is depressed and moving said dog 30 into engaging position with said wheel 40, substantially as described.

60 6. The combination of a support, a type 58, longitudinally movable therein, the pivoted hammer 48 in rear of said type and operating to press upon and longitudinally move said type, a motor, the spur-wheel 40, rotated by 65 said motor, a fixed support having the cam-groove 32, the movable dog 30, having a pin or roller traveling in said cam-groove and pro-

vided with a shoulder 39, disposed in proximity to said spur-wheel 40, the link 37, connecting said dog 30 to the hammer-lever, the pivoted bar 35, and retracting-spring 35*, extending between said dog and said bar 35, the pivoted lever 24 25, having at one extremity the slotted link 28, receiving a pin on said dog 30, and the finger-key 4, in proximity to 75 the other end of said lever and operating when depressed to move said end downwardly, thereby bringing the shoulder on said dog 30 into engaging position with the wheel 40, substantially as described.

7. The combination of a laterally-movable type, an impression-surface in front of said type, a pivoted lever 4, and mechanism interposed between said lever and said type, whereby when said lever is depressed said type is moved laterally to a new position before said surface, a motor, and mechanism between said lever and said motor whereby motion is communicated from said motor to said lever to depress said lever and so to move 90 said type as aforesaid, substantially as described.

8. The combination of a longitudinally-movable type, a movable support therefor, a vibrating hammer arranged in rear of said 95 type and operating to press upon and longitudinally move said type, a pivoted lever 4, and mechanism interposed between said lever and said type-support whereby when said lever is depressed the said type-support is 100 moved to carry said type into the path of said hammer, a motor, and mechanism between said lever and said motor whereby motion is communicated from said motor to said lever to depress said lever and so to move said type-support, as aforesaid, substantially as 105 described.

9. The combination of a longitudinally-movable type, a movable support therefor, a vibrating hammer arranged in rear of said 110 type and operating to press upon and longitudinally move said type, a pivoted lever 4, mechanism interposed between said lever and said type-support whereby when said lever is depressed the said type-support is moved to 115 carry said type into the path of said hammer, a motor, mechanism between said lever and said motor whereby motion is communicated from said motor to said lever to depress said lever and so to move said type-support, and a 120 means of detachably connecting said lever and said mechanism, substantially as described.

10. The combination of a longitudinally-movable type, a movable support therefor, a 125 vibrating hammer arranged in rear of said type and operating to press upon and longitudinally move said type, a pivoted lever 4, mechanism interposed between said lever and said type-support whereby when said lever 130 is depressed for a certain distance the said type-support is moved to carry said type into the path of said hammer, a motor, mechanism between said lever and said motor where-

by motion is communicated from said motor to said lever to depress said lever and so to move said type-support, and a locking device whereby said lever when pressed down 5 for a certain less distance than the distance aforesaid is automatically connected to said transmitting mechanism, substantially as described.

11. The combination of the rotary type-cylinder 57, vibrating plate 15, and belt 52, for communicating the motion of said plate to said cylinder, the key 4, having cam projection 12, acting on said plate 15 and provided with the hook 138, a motor, the rotary spur-wheel 40 actuated thereby, the pivoted lever 25 24, provided at one end with a means of engagement with the spur-wheel 40 and at the other end with a bar or plate disposed beneath the cam projection 12 on key 4, the locking-plate 134, the bent rod 135, supporting said plate and pivoted to lever 24, and the fixed rollers 136, through which said rod 135 passes, substantially as described.

12. In combination with an impression-surface, a type, and a means of moving said type to produce an indentation in said surface, a movable support for said surface, a pivoted lever 4, and mechanism interposed between said lever and support whereby when 25 said lever is depressed the said support is moved in front of said type to expose a new portion of the surface to indentation, a motor, and mechanism between said lever and said motor whereby motion is communicated from 30 said motor to said lever to depress said lever and so to move said support as aforesaid, substantially as described.

13. In combination with an impression-surface, a type, a means of moving said type 40 to produce an indentation in said surface, a movable support for said surface, a pivoted lever 4, and mechanism interposed between said lever and support whereby when said lever is depressed the said support is moved 45 in front of said type to expose a new portion of the surface to indentation, a motor, mechanism between said lever and said motor whereby motion is communicated from said motor to said lever to depress said lever and so 50 move said support, as aforesaid, and a means of detachably connecting said lever and said mechanism, substantially as described.

14. In combination with the carriage 96 and laterally-moving frame 118 119 120 thereon, 55 said frame having the rack-bar 122, the finger-key 133, rod 68, pivoted lever 69, rack-bar 94, jointed to lever 69, bent pivoted rack-bar 102, receiving and vibrated by the rack-bar 94, pinion 95, disposed between said rack-bars 94 and 102, and pinion 99, engaging with rack-bar 122, substantially as described.

15. In combination with the carriage 96 and laterally-moving frame 118 119 120 thereon, 60 said frame having the rack-bar 122, the finger-key 133, rod 68, pivoted lever 69, bent piv-

oted rack-bar 102, receiving and vibrated by the rack-bar 94, pinion 95, disposed between said rack-bars 94 and 102 and supported on shaft 98, pinion 99 on said shaft 98, engaging with rack-bar 122, and the pivoted bars 107 70 and 108, provided with springs 109 and 110 and with rollers at their ends bearing upon opposite sides of bar 94, substantially as described.

16. In combination with an impression-surface, a type, a means of moving said type to produce an indentation in said surface, the carriage 96, for supporting said impression-surface, provided with a dovetail projection 111, entering ways 112 in the bed 1, the nut 80 113 on said carriage, bearings 114 on said bed, and the screw 115, journaled in said bearings and received in said nut, substantially as described.

17. In combination with the carriage 96, 85 having the circular transverse chambers 130 and 131 and the upper transverse bar 128, the frame 118 119 120, and provided with a rack-bar 122, entering the chamber 131, and the roller 121, entering the chamber 130, and 90 the transverse bar 125, carrying the roller 127, said roller resting on the carriage-bar 123, substantially as described.

18. In combination with a motor, the rotary spur-wheel 40, actuated thereby, and the 95 vibrating pivoted hammer 48 38, the finger-key 4, pivoted lever 24 25, movable dog 30, linked to said lever and provided with a shoulder 39, cam-groove 32 in a fixed bracket and receiving a roller or pin on said dog, pivoted bent lever 35, and spring 35* between said lever and said dog, and link 37, pivoted to said dog and to the hammer-rod 38 and provided with a slot 37*, through which the pin connecting said link to said hammer-rod 100 passes, substantially as described.

19. The combination of the fixed rotary tubular support 50, the type-cylinder 57, containing type radially disposed and longitudinally movable therein and having the sleeve 110 63, surrounding said support 50, and the vibrating hammer 48 38 within said cylinder and said support, the said hammer acting upon said type to move them outwardly, substantially as described.

20. The combination of a rotary tubular support, a hammer pivoted and vibrating transversely therein, and two or more annular cylinders containing type radially disposed and longitudinally movable therein, 120 the said cylinders being interchangeably applicable to said support, and the said hammer, when either cylinder is upon said support, acting upon said type to move the same outwardly, substantially as described.

WILLIAM JAMES HOWELL.
